UNITED STATES PATENT OFFICE.

JOHN H. TRISMEN, OF NEW YORK, N. Y., ASSIGNOR TO CONSOLIDATED FIRE WORKS CO. OF AMERICA, OF NEW YORK, N. Y., A CORPORATION OF NEW YORK.

GRENADE OR BOMB.

1,243,781.

Specification of Letters Patent. Patented Oct. 23, 1917.

Application filed December 10, 1915. Serial No. 66,046.

To all whom it may concern:

Be it known that I, JOHN H. TRISMEN, a citizen of the United States, residing at New York city, in the county of Richmond 5 and State of New York, have invented certain new and useful Improvements in Grenades or Bombs, of which the following is a full, clear, and exact description, such as will enable others skilled in the art to 10 which it appertains to make and use the same.

My present invention relates to grenades or bombs, which are to be thrown by hand over moderate distances, and has for its 15 object to provide such a bomb of simple and comparatively cheap construction which may be handled with entire safety until it is desired to be exploded, when an easy manipulation will render it capable of immediate action. In addition, I provide 20 duplicate safety devices, so that in case of the failure of one of them, the other will nevertheless act to prevent accidents.

To these ends I provide an explosive 25 chamber and a tube extending therefrom containing a spring-actuated firing pin having a cord attached to its outer end. The pin is shorter than the tube, and through the wall of the tube and the pin I provide 30 registering perforations through which a detent, preferably in the form of a cotter-pin, may be passed, holding the firing pin out of contact with the firing device, which is usually a fulminating cap. The firing 35 pin being wholly disposed within the tube, dropping the bomb does not bring the blow upon the end of the pin either when the cotter-pin is in place or when it is not; but to insure safety of the device while it is 40 being transported or against accidental shocks before it is adjusted to be exploded, I seat the fulminating cap upon a reversible anvil seated in a fuse tube, so that when the device is transported, the anvil is reversed 45 so that the dead side of the cap comes against the fuse, and fire cannot reach the latter, even should the cap be exploded. Either of these arrangements provides a safety device preventing any accidental actuation of the firing devices until the desired time.

Within the explosive chamber, I provide 50 an interior receptacle, such as a sheet metal can, containing preferably the explosive known in the art as "TNT" (trinitrotolu-

ene), and located in the end of the can, and projecting into the body of the explosive is a detonator or fulminating cap, which is ignited by the combustion of the fuse. Between the can and the outer wall of the explosive chamber, I may arrange bullets or slugs of any kind.

The accompanying drawings show my improved grenade,

Figure 1, being a side elevation; and 65
Fig. 2 a longitudinal section thereof.

A is the chamber for explosive, sealed by a cap A¹. This is usually of cast iron, since that answers well enough for the short range to which these devices are usually effective, 70 though other substances may be used. B is a sheet metal can within which is the charge C of TNT, and between the can and the wall of the explosive chamber are arranged bullets or slugs A². The end of the tube I 75 preferably has a recessed portion, upon which is placed a detonator or fulminating cap D, having a charge D¹ of fulminate in the lower end thereof. In practice the charge C is so shaped as to admit the cap, 80 being bored out for this purpose, the explosive being packed tight in the can.

E is a fuse, fitted into the fuse-tube I, the composition and length of which is selected to give the desired time for the explosion of 85 the bomb, 2 or 3 seconds, for example. It is well understood in the art that the explosive named will not explode from combustion, but only by detonation, and therefore the fuse serves only to explode the fulminating cap D referred to. At the upper end of the fuse-tube is an opening, in which is seated the anvil I', and the tube, as will be seen, is slightly relieved at I². A fulminating cap K is seated in the anvil. By 90 preference the anvil is cylindrical, because that is the most convenient and cheapest shape to make; but it may, of course, be polygonal, or any other shape, preferably symmetrical. The anvil is capable of reversal, and the cap may be disposed with its dead side adjacent to the fuse E in the relieved portion of the fuse-tube I. A boss A³, preferably formed integral with the explosive chamber A, is threaded upon its 100 outside, and is bored to admit the fuse tube I.

A tube F extends from the chamber A, and is provided at its lower end with an enlarged portion F' threaded upon the interior so as to screw upon the boss A². As 110

will be obvious, this also secures the fuse-tube I in position. Disposed within the tube F is the firing-pin G, having at its upper end a hole G² in a portion of the end of 5 the pin which is slightly cut away; in the hole is the cord H for manipulating the firing-pin. The cord is provided with a button H' upon the end so that it can easily be held in the grasp of the hand. Disposed 10 around the pin G is the helical spring G¹ pressing at its upper end against the end of the tube F and at its lower end against a collar G⁴ upon the firing-pin; the latter is pointed at the end G³, so as to 15 explode with certainty the fulminating cap K. In the wall of the tube F is a perforation, and a corresponding perforation is made in the pin G. When these are brought into registry, the cotter-pin g is placed therein, thus holding the firing-pin out of contact with the cap K. In the enlargement F¹ is a hole f, and in the wall of the fuse-tube is a registering hole i providing a vent in case of the accidental explosion of the 20 fulminating cap when in its reversed position. Ordinarily these may be omitted, if desired.

The operation of my improved grenade is as follows: When the parts are in the 30 position shown in the drawing, and it is desired to explode the device, the cotter-pin G is pulled out and the grenade is swung on the cord H until the firing-pin is practically completely withdrawn from the tube, 35 the centrifugal force compressing the spring G¹ until its coils touch one another. When the pin is thus withdrawn to the limit, the device is thrown toward the enemy's position and the release of the cord permits 40 the spring to force the pin down upon the fulminating cap, which is in the position illustrated in Fig. 2 at this time. This fires the fuse, which may be set for such time as is desired, two or three seconds, for example, and when the fire reaches the 45 fulminate, the latter detonates and the bomb is exploded.

When the device is to be transported, the anvil I¹ may be reversed with the dead 50 surface of the cap adjacent to the fuse and the pin g is placed in position. When the grenades are distributed to the troops, the tube F may be unscrewed and the anvil reversed. Immediately before it is desired to use the 55 grenade, the cotter-pin G is removed. The removal of the cotter-pin does not serve to permit the firing pin to be urged by the spring against the cap, since the firing pin

is adjusted to remain normally out of engagement therewith. Thus if a soldier 60 about to throw a grenade should be struck, and the grenade fall, it would not explode, since the firing pin can only be forced into engagement with the cap through the compression and sudden release of the spring. 65

Many changes might be made in the arrangement without departing from the invention, as will be obvious to those skilled in the art.

Having described my invention, what I 70 claim as new and desire to secure by Letters Patent is:

1. In a grenade, a chamber, a fuse-tube extending into the chamber, a reversible anvil seated in the outer end of the fuse-tube, the tube being relieved thereunder, a fuse in the tube, and a fulminating cap upon the anvil, whereby when the grenade is to be transported, the anvil may be reversed so that the cap is disposed in the 80 relieved portion of the fuse tube with its dead side adjacent to the fuse.

2. As a new article of manufacture, a grenade comprising a chamber for explosive, a tube extending therefrom, a firing pin in the tube, and a spring pressing the pin toward the chamber, with a fuse-tube extending into the chamber, and a reversible anvil carrying a fulminating cap seated in the end of the fuse-tube away from the 90 chamber.

3. As a new article of manufacture, a grenade comprising a chamber for an explosive, a reversible anvil, a fuse-tube, a seat therein for the anvil, a firing-pin, a 95 spring therefor, and removable means for retaining the pin out of contact with the anvil and wholly within the tube until the grenade is to be exploded.

4. As a new article of manufacture, a 100 grenade having a chamber for explosive, a tube extending therefrom, a firing-pin in the tube, and a spring pressing the pin toward the chamber, with a cord attached to the outer end of the pin, whereby when the 105 grenade is swung by the cord, the centrifugal pull thereon stores energy in the spring, and when the cord is released, the pin is forced by the spring toward the chamber to fire the explosive. 110

In testimony whereof I affix my signature, in the presence of two witnesses.

JOHN H. TRISMEN.
